(57) **CLAIM**

The ornamental design for a split-screen display device as shown and described.

DESCRIPTION

FIG. 1 is a top front left perspective view of a split-screen display device, showing my new design.

FIG. 2 is a rear, right and bottom perspective view thereof.

FIG. 3 is a front elevation view thereof.

FIG. 4 is a rear elevation view thereof.

FIG. 5 is an enlarged left-side elevation view thereof.

FIG. 6 is an enlarged right-side elevation view thereof.

FIG. 7 is an enlarged top plan view thereof.

FIG. 8 is an enlarged bottom plan view thereof.

FIG. 9 is an enlarged view of detail 9 in FIG. 2.

FIG. 10 is another top front left perspective view of the split-screen display device of FIGS. 1-9 in a first position of use.

FIG. 11 is a rear, left and top perspective view of the split-screen display device of FIG. 10.

FIG. 12 is another rear, left and top perspective view of the split-screen display device in a usable state.

FIG. 13 is another rear, left and top perspective view of the split-screen display device of FIG. 1 in a second configuration of use.

FIG. 14 is another rear, left and top perspective view of the split-screen display device of FIG. 1 in a third configuration of use.

FIG. 15 is a front perspective view of the split-screen display device of FIG. 1 in a folded configuration; and,

FIG. 16 is a rear perspective view of the split-screen display device of FIG. 15.

The dashed broken lines depict portions of the split-screen display device that form no part of the claimed design.

(Continued)

The dot-dash broken lines in FIGS. 1 and 9 represent the extents of the enlarged detail view and form no part of the claimed design.

1 Claim, 16 Drawing Sheets
